DESIGN FOR A DECORATIVE ILLUMINATING UNIT

Merrill A. Yohe, New Oxford, Pa.

Application October 20, 1933. Serial No. 49,526

Term of patent 14 years

To all whom it may concern:

Be it known that I, MERRILL A. YOHE, a citizen of the United States, residing at New Oxford, in the county of Adams and State of Pennsylvania, have invented a new, original, and ornamental Design for a Decorative Illuminating Unit, of which the following is a specification, reference being had to the accompanying drawing, forming part thereof.

I claim:

The ornamental design for a decorative illuminating unit, as shown.

MERRILL A. YOHE.
